Application January 26, 1946, Serial No. 643,713

5 Claims. (Cl. 84—174)

1

This invention relates in general to pianos and more particularly to a piano structure including simple, rugged, and lightweight preassemblies which lend themselves to high speed production utilizing assembly-line methods which not only provide an improved piano construction with uniform parts, but also provide an improved piano construction with assemblies which can be put together and taken apart for greater ease in original manufacture, in shipping, and then in subsequent handling in a store and home.

Heretofore, it has been customary to manufacture pianos largely on an individually customized basis. This has been due primarily to the nature of commercial piano construction and to the difficulty in producing in such construction, the desired uniformity of tonal quality and performance. Different practices were introduced to speed up piano manufacture, but it still remained an operation wherein each piano was normally slightly or considerably different as a result of hand-fitting certain portions at least, and generally was characteristic of the individuals working upon it. Except in the most expensive pianos, there was often marked lack of uniformity among the pianos as far as playing quality, stability of tuning, and the like was concerned. The efforts which have been made prior to the present development as evidenced in this invention as well as those inventions of my copending application Serial No. 585,053 filed on March 27, 1945 and my Patent No. 2,431,350 granted on November 25, 1947, to provide a piano construction lending itself to high speed uniform production have been notably unsuccessful. Furthermore, the efforts to construct a knock-down type piano in which the operating and playable parts can be manufactured entirely independently of the casing or housing unit have also been unsuccessful, and no such concept has heretofore been put into practice commercially. The present existing practice wherein the casing serves to assemble and retain many of the parts during the manufacture of a complete piano requires that special care be taken of the piano casing during manufacturing resulting in a less efficient manufacturing procedure from the standpoint of labor and material costs. Not only is handling in manufacturing complicated but scratches and nicks must be repaired before shipment, and even after the piano is received in a store or in a home. Also, the requirements that the entire piano be assembled during manufacture in order to provide a satisfactory instrument has complicated shipment because of the bulk of the completed product.

In general, in prior commercial piano construc-

2

tion, the string support of the instrument has comprised a frame, called a plate or harp of cast iron, and a pin block and sounding board which with pins on the block and plate altogether carry and stretch the strings. These parts are mounted on a stiff massive wood back. This is necessary in order to provide a back frame strong enough to resist the tremendous force exerted by the piano strings which on an average is 17 tons per piano. Also, it has been customary to utilize the piano case to maintain these parts in assembly and to support the keys and piano action so that a sturdy glued case was required. This rugged casing along with the heavy cast iron and wood back structure has contributed to the undesirable high over-all weight of the piano instrument.

Pianos in the past have represented an expensive instrument. The average family in a lifetime purchases no more than two pianos, and often just one. However, because of changing styles in the home over a long period of time, the case for a piano purchased in one era is not attractive in another era of style and decoration. The operating parts, except for the usual repairing, are often in good condition, but the case which has been in the past an integral part of the structure, spoils the appearance of the instrument and sometimes relegates it to a back room and disuse if the family is unable to afford a completely new piano. Even where a piano owner is willing to change casings because of a particularly high quality operating mechanism the cost of a new case is excessive both in removing the old case and hand fitting a new case to non-uniform operating structure.

It is an object of this invention, therefore, to provide a new and improved knock-down type piano of high quality having uniform tonal and performance characteristics over large numbers of corresponding instruments.

Another object of my invention is to provide operating structure and a casing with parts and subassemblies of such construction as to lend themselves to precision machine-made manufacture.

It is another object of the invention to provide a piano construction having one preassembled portion comprising all of the operating parts which is entirely self-supporting and playable, and which has provisions thereon for connecting with a casing or cabinet in a manner such that the casing or cabinet can be used only to style the piano.

It is a further object of this invention to provide a new and improved string chassis or sub-

assembly complete with sounding board and strings which is light enough to be readily handled by one person and completely self-supporting in an upright position so as to readily receive for assembly therewith the remaining operating parts of a piano.

It is also an object of my invention to provide a piano mechanism which lends itself to high speed assembly line manufacturing methods without sacrificing tonal quality, stability of tuning, uniform key and action operation, or any other essential feature of a high quality hand made piano.

A feature of my invention is the provision of a small number of precision-made subassemblies which fit together in a high speed production-line manner, and each contribute to the production of a lightweight piano in standard sizes, which is readily demountable into the subassemblies for shipping and handling.

Another feature is the provision of a preassembled operating portion which is entirely capable of playing operation in a normal manner, and which may be combined with a housing or casing portion, each of which portions includes provisions for connecting the two portions together to style the operating portion in any one of a wide variety of interchangeable housing or casing portion designs.

An additional feature of my invention is the provision of supports and connecting means for the light weight subassemblies and the housing such that one man can readily assemble or disassemble the entire piano, and similarly quickly change housings on the operating part of the piano to change the styling thereof to suit the changing desires of the owner.

A further feature of the invention is the provision of a unitary string-chassis including a rigid self-supporting light metal frame member which together with a sounding board and a pin block supported on the frame member, form the sole means for mounting and stretching the piano strings, and for resisting the tremendous forces caused by the tension of the strings. In a commercial embodiment of the invention the weight of the complete assembly is less than one-half ($\frac{1}{2}$) of the weight of comparable structure heretofore universally used in the piano industry.

A still further feature of this invention is the provision of means on such unitary string-chassis or assembly to support the same in an upright position and which is manually operable and adjustable during the initial assembly of the chassis and while other sub-assemblies are being connected thereto.

It is also a feature of my invention to optionally provide means for securing to the light-weight metal frame member of the string chassis as a cross-support to permit the lightest possible weight thereof, and yet support such frame member in a manner to withstand the tremendous tension exerted from corner to corner thereon when the playing strings are tightened to operating tension. On a small upright piano chassis, the tension is as much as 8,000 pounds, and this will increase during playing.

For a better understanding of the invention, together with further objects, features and advantages thereof, reference is had to the following description taken in connection with the accompanying drawings in which:

Fig. 1 is a perspective view of the self-supported piano operating structure in its final as-

sembled condition and capable of being played in such condition.

Fig. 2 is a cross-sectional view approximately along the lines 2-2 of Fig. 1 but with the removable front supporting leg omitted.

Fig. 3 is a partially exploded rear perspective view of a complete low upright piano using the operating unit of Fig. 1.

Fig. 4 is a perspective view of the light weight metal frame member of the structure of Fig. 1 and illustrates the horizontal brace member therefor which is not visible in Fig. 1.

Fig. 5 is a perspective view of the frame member having a modified form of cross bracing.

Fig. 6 is a front view of the frame member of Figs. 1 to 5 showing the supporting feet secured thereto in a projecting supporting position as contrasted to the folded position of Fig. 1.

Fig. 7 is a side view of one of the feet of Fig. 6 and,

Fig. 8 is a perspective detail view of a foot.

For purposes of illustration, my invention will be described herein as applied to a low upright piano, but it is to be understood that the invention is not limited thereto. This piano includes an operating unit which comprises a string chassis including a unitary light weight metal frame member with a sounding board and pin block mounted thereon adapted to carry and stretch the full complement of strings for playing. The string-chassis has retractable feet for supporting it in an upright position as a sub-assembly and the sub-assembly is adapted to have mounted thereon a key bed supporting keys and an action in playing position relative to the strings to in all make up the playing unit. The front portion of the playing unit is secured to the frame member by brackets removably mounted on the front side of the string-chassis. The pedals and mechanism therefor are supported from the frame member and key bed so that a complete playable piano is provided which can be completely and finally regulated during the manufacture of the entire playing or operating structure.

The frame member of the string-chassis comprises a wide peripheral flange with a web portion internally of the flange and intermediate its edges from front to back. Provisions are made on the chassis and on the flange for positioning the sides and top of the piano case and removably retaining said members. The remaining parts of the piano case are secured to the side members or operating structure to form a complete demountable case for the piano which is readily interchangeable in various case and leg designs to style the piano to the owner's taste.

Referring now to the drawings, Fig. 1 shows the operating structure comprising a string chassis 10, a key bed 11 secured thereto by brackets 12, and a playing unit 13 supported by said key bed and string chassis. As can be seen in Fig. 2, the string chassis includes a frame part 14 having a peripheral flange 14a and a web portion 14b. The peripheral flange extends completely around the frame portion as is clearly shown in Fig. 4. The web portion is positioned substantially centrally of the peripheral flange. On the back of the frame are positioned a pin block 15 and a sounding board 16. The pin block 15 is positioned in a channel-like recess formed by the upper flange 14a and a second flange 14c secured to the web portion of the frame and parallel to the upper flange. The sounding board 16 is positioned between the flange 14c and the lower per-

75

peripheral flange 14a to cover the remainder of the space on the back of frame 14. As shown in Fig. 3 the sounding board 16 is provided with ribs 16a for making the same more rigid over certain areas. For securing the sounding board to the web portion of frame 14, screws 17 or the like are provided.

Openings 14d are formed in the web portion 14b of the frame, in the recess between flanges 14a and 14c, to allow the string pins 18 in the pin block 15 to project through to the front of the web portion. The adjustable string pins 18 cooperate with fixed string pins 14e on the web portion of the frame member (Fig. 1) to support the piano strings. Bridges 16b and 16c, for the base and treble strings respectively, are provided on the front face of the sounding board and project through openings in the web portion of the frame member to the front thereof to contact the strings.

The frame member 14 is preferably constructed of a high tensile strength, light metal alloy such as an aluminum-copper-magnesium alloy commercially available as "Duralumin," or an alloy of magnesium, aluminum, manganese and zinc commercially available as "Dowmetal." In any event the member 14 should be constructed of a material and with a cross sectional moment of inertia resulting in a resiliency for a given weight substantially higher than that of a composite cast iron frame and wooden back of the standard piano. Preferably the material of the frame member 14 should have a ratio of Young's modulus to specific weight greater than 3×10^6 and preferably of the order of 3.75×10^6 . This ratio may be termed the "factor of merit" and is an index of the rigidity per pound of metal of the chassis member for any given size and for any given cross-sectional configuration. In other words, a string chassis of given dimensions made of a metal with a high ratio will have a higher rigidity for any given weight or will be lighter in weight for any given rigidity than one made of a metal having a lower ratio. The mean value for aluminum alloy of the type mentioned is 3.89×10^6 while a typical value for a magnesium alloy of the type mentioned is 3.57×10^6 .

In one commercial embodiment of the invention, a frame member as shown in Fig. 6 for a 38" low upright piano weighs 80 pounds in a magnesium alloy. The complete string-chassis complete with strings, sounding board and pin blocks as shown upright in Figs. 1 and 2 weighs approximately 135 pounds. As the conventional structure for the same size piano having a cast iron frame backed with wood supporting members weighs approximately 285 pounds, it can be seen that by utilizing a construction in accordance with this invention a reduction of the order of 150 pounds will result in the back structure alone. This particular commercial embodiment corresponds in size to what is known in the industry as a "38" low upright piano."

Reference is now made to Fig. 4 which shows in detail the construction of the frame 14. As shown in this figure the web portion has a plurality of openings therein to lighten the weight of the frame member and a plurality of integral bracing struts 14f to provide strength at the points where it is needed. The tension of the strings on the frame causes a tremendous corner to corner force tending to twist or buckle the frame. The bracing struts are positioned where they will be most effective in resisting this force.

An additional horizontal bracing member 30

may be positioned on the front side of the frame member and secured to the peripheral flange 14a and the bracing struts 14f as shown in Fig. 4. This bracing member serves the dual function of reinforcing the frame member 14 and of cooperating with the brackets 12 to support the key bed and action of the piano. The bracing member is secured to the frame member in abutting relation with the struts 14f so that a portion of the bracing member is positioned within the space defined by the peripheral flange 14a. This provides a maximum of reinforcement for the frame member. Clearance is provided between the frame and the bracing member in the space not occupied by the struts to permit the strings to extend from corner to corner as illustrated in Fig. 1.

Fig. 5 shows an alternative structure in which an X-shaped brace or member 31 is used to provide the same function as the horizontal brace member 30. The member 31 is secured to the frame member at the flanges thereof, and at the reinforcing struts as shown. The reinforcing member is positioned at the lower part of the frame structure so that it does not interfere with the piano action and is also positioned so that a part thereof is within the space defined by the flange 14a to provide maximum support.

The playing unit of the piano including the keys 30 and action is supported on the key bed 11. A split key bed is provided having a rear portion 11a and a front portion 11b. The rear portion 11a includes pins 19, to support the action brackets 29, which in turn carry the stationary and movable parts on the action itself. Except to refer to the whip 21 and the hammer 22 in each individual unit of the complete action, and likewise the pivoted hammer rest rail 23 and the stationary rail 24, common to all units, there is no necessity for describing more in detail the action illustrated. Threaded pins or bolts 25 secured to the frame member receive and support the top of each of the plurality of action brackets 29, all as shown in Fig. 1. The front part of key bed 11b supports a key frame 26 on which are pivotally mounted a plurality of keys 27. A capstan screw 28 is provided at the end of each key for engaging a whip when a key is depressed in playing and sets into motion the action of that unit including the hammer 22 which strikes the corresponding string. The vibration of the string is transmitted through the bridge 16b or 16c to the sounding board where the sound produced by the vibrating string is amplified.

As previously stated, the key bed is secured to the string chassis by brackets 12. As shown in Fig. 1, the brackets include body portions 12a having integral right angle flanges 12b which are secured to the web portion of the frame member. Slot shaped openings 12c are provided in the flanged portion 12b for bolts 29 which enter the reinforced web portion 14g, as shown in Fig. 1. The brackets 12 are adjustable on the bolts 29 for the proper vertical height relative to the string-chassis so that the keys and action are properly positioned relatively to the strings. The brackets include an upper face or surface 12d for supporting the key bed, with an integral extension 12e extending forwardly therefrom and offset inwardly of the key bed relative to the back and body portion 12a as is evidenced from Fig. 1. The bracket may also include a notched portion 12f into which a horizontal supporting member 30, which has been previously described, is adapted to fit. It is evident that the brackets

12 provide an adjustable connection between the string chassis and the playing unit of the piano operating structure as well as the support for the playing unit.

By use of the invention, the space within the flanges 14a and in front of the web portion 14b above the bracing member 30 (Figs. 1, 2, and 4) or 31 (Fig. 5) comprises a cavity into which the piano action may extend. This cavity is of depth equal to nearly one-half the over-all width of the frame member 14 and permits construction of a more shallow piano with the action and key bed extending into the frame member cavity. That is, it permits of a more shallow piano from front to back without sacrificing key length. This is a very important feature as it is desirable to keep the width of low upright type pianos to a minimum so that the piano will require a small amount of space in a room, may be taken through standard doorways, and in general is more easily handled in a small apartment, or any other home setting as a matter of fact. On the other hand by increasing the length of the keys, greater leverage is provided and an action which is unacceptably stiff and unnatural when operated by a short key might become entirely acceptable if the key length is increased to provide a greater leverage. This invention permits a longer key in comparison to that in a standard width conventional prior piano construction.

Considering specific typical dimensions, in a piano having a width of 23 $\frac{3}{4}$ inches, it is possible to increase the length of the key from 15 inches to 16 $\frac{1}{2}$ inches and retain the same overall width by utilizing the unitary string chassis of this invention instead of the standard composite frame. This increase in key length will greatly improve the operation of the piano action. Alternatively by utilizing the same key length it is possible to reduce the width of the piano by 1 $\frac{1}{2}$ inches which will result in a material saving in space.

As shown in Figs. 1, 6, 7, and 8, feet 32 are secured to the frame for supporting the string-chassis during the preliminary stages of assembly and for supporting the structure in an upright position when the housing or casing is being secured thereto. As shown clearly in Figs. 7, and 8 the feet 32 comprise upright angle members 33 secured to the frame 14 by bolts 33a, and having angle members 34 hinged thereto. The members 34 have bearing portions 34a thereon for resting on the floor on which the structure is supported and have latching members 35 secured thereto with top portions 35a adapted to fit in the notches 33b on the upright members. As is shown in Fig. 1, the latching members may be released and the projecting members 34 hinged upwardly against members 32 so that the feet are positioned against the frame member 14. When in this position, the feet can be completely covered by the removable bottom frame, as it is called, of the casing of the piano and will be out of sight.

As previously stated, the feet secured to the frame member may be used to support the string chassis during the preliminary stages of assembly of the operating structure. After assembly of the brackets 12 on the preassembled string chassis of the operating structure and thereafter the assembly of the key board and associated elements or units including the action itself on the brackets, legs 48 are connected to the front part of the playing portion to support the complete operating unit for movement in the remaining manufacturing steps.

In the disassembly of a complete piano for shipment or moving, when the casing is removed from the operating structure of Fig. 1, then as the operating structure is taken apart the feet 5 are dropped down to the position of Fig. 7 with the arm 35 in a notch such that with legs 48 removed and the string-chassis 14 standing alone, it leans forward very slightly to prevent the string-chassis from being tipped over backward.

10 The angle at which the string chassis rests is exaggerated in Fig. 7 for the purpose of illustration.

In Fig. 3 is shown the assembly of the cabinet on the operating structure of the piano. As previously stated, the feet secured to the frame member

15 member are used to support the operating structure while the casing is being secured thereto. The cabinet includes side members 36, a top member 37, and a front frame 38 which includes 20 a music shelf. The fall board which pivots out of the top frame and down over the keys is not visible in the illustration. Key blocks 47 are provided at each side of the keys while a key slip 47a extends across the front of the keys. 25 Included in the demountable casing is a removable bottom frame below the key bed and over the face of the bottom of the string-chassis. A toe rail 45 supports the pedals 46 and associated mechanism as shown in Fig. 1.

30 The side members 36 are provided with dowels 36a which are adapted to fit in openings 14h in the flange of the frame member 14 for positioning the members with respect to the frame as shown in Fig. 1. Corresponding hinge-like members 35 and 40 are secured to the side members 36 and the pin block and sounding board with removable pins 41 for securing the members together. Similar members are provided for securing the front of the side members, the exact position of which 40 depending on the style of the cabinet. The top member or frame 37 is secured to the top of the frame member 14 by hinges 42 shown in Figs. 1 and 3. The front parts of the piano casing as previously identified are secured to the side members 45 by readily disconnectable means to provide a casing structure which can be easily assembled or disassembled.

From the foregoing description, it can be seen that a knock-down type piano is provided in 50 which the various operating parts and the cabinet parts may be prefabricated and shipped in a knock-down condition for assembly by unskilled labor at a sales room or even the home of the user. In a fully representative operation a cabinet as 55 illustrated in Fig. 3 was removed from the operating structure of that figure, and a Victorian style cabinet substituted thereon in approximately 15 minutes and skilled help can do it in less. The various components are arranged for

60 production-line manufacture in such a manner that a uniform and high quality instrument will be provided. The string-chassis is so constructed that the weight thereof is reduced to a minimum to facilitate manufacture, and also assembling of 65 the unit after being shipped to the seller or user. The provision of the self-contained feet for supporting the string chassis while assembling the subassemblies into the complete operating structures, makes for a great ease and simplicity in 70 manufacturing and assembly or disassembly. Although the frame structure is of simple construction and light in weight, it is sufficiently rugged with the integral struts, and optionally with the bracing member to resist the great strain 75 thereon due to the tension of the piano strings.

Although the description has been limited to what is at present considered the preferred embodiment of the invention, it will be apparent to those skilled in the art that various changes and modifications may be made therein and the scope of the invention should be limited only as defined by the appended claims.

I claim:

1. A unitary string chassis for a piano including a rigid metal frame having continuous wide peripheral flanges and a web portion, said web portion throughout its entire extent being disposed in a single plane approximately centrally of said peripheral flanges and integral therewith, a sounding board, means supporting said sounding board on said frame on one side of said web portion within the space defined by said peripheral flanges on said one side, piano strings, means supporting said piano strings on said frame on the side of said web portion opposite to said one side, brace means on said opposite side of said web portion spaced from said piano strings, means securing said brace means to the flanges on opposite sides of said frame and to said web portion, said strings being positioned between said web portion and said brace means, at least a portion of said brace means being positioned within the space defined by said peripheral flanges on said opposite side of said web portion.

2. Operating structure for a piano comprising a string chassis and a playing unit, said string chassis including a rigid metal frame member having continuous wide peripheral flanges and a web portion, said web portion throughout its entire extent being disposed in a single plane approximately centrally of said flanges and integral therewith, a sounding board and a pin block, means for supporting said sounding board and pin block on said frame on one side of said web portion within the space defined by said peripheral flanges on said one side of said web portion, a horizontal brace member on the side of said web portion opposite to said one side, means for securing said brace member to said flanges and said web portion, piano strings, means supporting said strings on said frame with said strings being positioned between said brace member and said web portion, and means including said brace member for supporting said playing unit on said string chassis on said opposite side of said web portion, said strings and at least portions of said brace member and said playing unit extending into the space defined by said peripheral flange on said opposite side of said web portion, said brace member thereby serving to reinforce said frame member and to support said playing unit.

3. A knock-down type piano comprising a casing and operating structure capable of standing upright in assembled condition independent of the casing, said operating structure including a string chassis having a rigid metal frame member, a sounding board, piano strings, and means for supporting said sounding board and strings on said frame member, a playing unit, means for removably securing said playing unit to said string chassis, retractable feet members having first stationary portions and second portions pivotally connected to said first portions, said first portions including notches therein and said second portions including members adapted to selectively engage said notches for adjustably positioning said second portions with respect to said first portions, and means for securing said first portions to said frame member with said second portions being pivotable away from said

frame member to support said string chassis in an upright position while said playing unit is secured thereto, and to support said entire operating structure in an upright position while said casing is being assembled thereto, said flange and casing including registering provisions for positioning said casing with respect to said operating structure, and means for removably connecting said casing and operating structure.

10 4. A knock-down type piano comprising a casing and an operating structure capable of standing upright in assembled condition independently of the casing, said operating structure including a string chassis having a rigid metal frame member, a pin block, a sounding board, piano strings, and means for supporting said pin block, sounding board and strings on said frame member, a playing unit including a key bed, means for removably securing said playing unit to said string chassis, legs for said operating structure, means for removably securing said legs to said key bed, retractable feet, means for securing said retractable feet to said frame member with said feet being adapted when in extended position to hold said string chassis in upright position while said playing unit and legs are assembled thereto, said operating structure including said legs being entirely self-supporting and being adapted to be entirely regulated and played in a normal fashion independently of said casing, said casing including end members and horizontal members, said flange and said end members including registering provisions for positioning said end members with respect to said flange and for securing said end members to said flange, said end members having provisions for supporting said horizontal members thereto, said feet being retracted prior to assembly of said horizontal members to said end members and being enclosed by said horizontal members.

30 5. A piano structure for use in an enclosing case, said piano structure comprising a rigid metal frame having peripheral flanges with a web structure integrally connecting the same and substantially in a single plane centrally of said flanges, string supports on said frame, piano strings secured to said supports, a sounding board, means for securing said sounding board to said frame, a key bed having keys supported thereon, means for supporting said key bed including brackets secured to said frame and extending forwardly thereof, a piano action, means for supporting said piano action on said frame in cooperative position with respect to said keys and in operative playing engagement with said strings, supporting means in front of said frame including a fixed portion and a bipart retractable portion, means for securing said fixed portion to said rigid metal frame, and means on said rigid metal frame and on said keybed for detachably securing a case thereto, said retractable portion having an operative position for supporting said piano structure and a retracted position within the space enclosed by the case.
